UNITED STATES PATENT OFFICE.

WILLIAM F. DORRIDA, OF BALTIMORE, MARYLAND, ASSIGNOR OF ONE-HALF TO
CHARLES S. SUTHERLAND, OF BALTIMORE, MARYLAND.

DIRECTION-INDICATOR.

1,383,192.

Specification of Letters Patent. Patented June 28, 1921.

Application filed November 12, 1919. Serial No. 337,441.

To all whom it may concern:

Be it known that I, WILLIAM F. DORRIDA, a citizen of the United States, residing at Baltimore, in the city of Baltimore and State 5 of Maryland, have invented certain new and useful Improvements in Direction-Indicators; and I do hereby declare the following to be a full, clear, and exact description of the invention, such as will enable others 10 skilled in the art to which it appertains to make and use the same.

This invention relates to new and useful improvements in direction indicators of the character employing an indicator adapted 15 to be moved in either direction for indicating a turn to the left or right and has for one of its objects the provision of an efficient electrical operating means which consists of a few parts so as to make the device extremely 20 inexpensive to manufacture and one that will correctly operate under all conditions.

With these and other objects in view as will become more apparent as the description proceeds, the invention consists in certain 25 novel features of construction, combination and arrangement of parts as will be hereinafter more fully described and claimed.

For a complete understanding of my invention, reference is to be had to the following description, and accompanying drawings, in which—

Figure 1 is a front elevation of a direction indicator constructed in accordance with my 35 invention,

Fig. 2 is a rear elevation of the same,

Fig. 3 is a transverse sectional view illustrating the electrical means for operating the indicator in either direction,

Fig. 4 is a perspective view of a bifurcated lever carrying the armature,

Fig. 5 is a perspective view of a balancing lever and its supporting bracket,

Fig. 6 is a vertical sectional view illustrating the device.

Referring in detail to the drawings, the numeral 1 indicates a casing adapted to be secured to an automobile in any desired manner and at any desired point upon the automobile so that the casing will be in clear view to the traffic about the automobile. The casing 50 1 has a front window 2 and a rear window 3, and which rear window is of a size considerably smaller than that of the front window. A supporting plate 4 is arranged 55 within the casing 1 and has positioned in the front of the same a front dial 5 and which is directly in rear of the front window. A rear dial 6 of a similar construction to the front dial is arranged in rear of the rear window. 60 A shaft 7 is journaled in the supporting plate 4 and extends through the front and rear dials 5 and 6 and has secured to its ends indicators 9 which may be of any desired design and in this instance I have elected to 65 show them in the outline of an arrow. The front indicator 9 is of a size considerably larger than the rear indicator to correspond with the front dial. The rear indicator is for the purpose of indicating to the driver 70 of the respective automobile if a correct signal is being given by the front indicator.

A supporting bar 10 is secured to the supporting plate 4 in spaced relation thereto and has journaled therein the shaft 7. The shaft 75 7 has formed therein a crank 11 which is disposed between the supporting bar 10 and the supporting plate 4.

An operating lever 12 is pivotally mounted between the supporting plate 4 and the 80 bar 10 and has its free end bifurcated as illustrated at 13 to receive the crank 11 of the shaft 7. The lever 12 is constructed of suitable insulating material and has secured thereon an armature 14 which extends 85 to a point adjacent the bifurcation. The armature 14 is provided with laterally extending wings 15 on each side thereof to be attracted by magnets 16. The magnets 16 are secured to supporting blocks 17 secured 90 to the supporting plate 4 on each side of the lever 12. The blocks 17 are constructed from suitable insulating material. The armature 14 has formed thereon a downwardly depending wing 18 that terminates adjacent 95 the bifurcated end 13 of the lever 12, and its end comes in close proximity to the crank 11 of the shaft 7 when the indicators 9 are swung into signaling position. The magnets 16 are adapted to be energized separately in any well known manner and when one of the magnets are energized it will attract the armature 14 swinging the lever 12 100 in the direction of the same, causing the

shaft 7 to be rotated and to move the indicators 9 into horizontal position. To move the indicators in an opposite direction, the other magnet is energized. A bracket 19 is 5 secured to the plate 4 and has one end enlarged and disposed at right angles as illustrated at 20, and said end is provided with an elongated slot 21. A balancing lever 22 is pivoted to one end of the bracket 19 and 10 extends through the slot 21 and has its other end provided with a notch 23 adapted to receive the crank 11 of the shaft 7. The walls of the notch 23 are inclined so as to permit the balancing lever 22 to ride freely on the 15 crank 11. The lever 22 is provided with an elongated slot 24. A weight 25 is slidably mounted on the lever 22 at a point of the formation of the slot 24 and is provided with a set screw 26 that extends through the 20 weight and slot 24 and is threaded into a locking plate 27 so that on screwing the screw home, the plate will be forced into engagement with the lever locking the weight against accidental movement on the 25 lever 22. Having the weighted lever 22 in engagement with the crank 11 of the shaft 7 will return the indicators 9 to their non-signaling or vertical position when the magnets are deenergized.

30 Lamp socket brackets 28 are secured to the front and rear faces of the plate and adapted to support electric lamp sockets 29 that receive electric lamps 30. The electric lamps 30 are for the purpose of illuminating 35 the dials in the indicators 9 at night time.

These electric lamps are furnished with electrical current from any suitable source.

While I have shown and described the preferred embodiment of my invention, it will 40 be understood that minor changes in construction, combination, and arrangement of parts may be made without departing from

the spirit and scope of the invention as claimed.

Having thus described my invention what 45 I claim is:—

1. A direction indicator including a casing, a supporting element in said casing, a shaft journaled in said supporting element, a crank formed on said shaft, an indicator 50 secured to said shaft, an operating lever pivoted to the supporting element and having a bifurcated end to receive the crank, electrical means for oscillating the lever, a bracket secured to the supporting element and having one end disposed at right angles and provided with a slot, a lever pivoted to said bracket and extending through the slot and having a notch provided with inclined walls 55 formed in its lower edge to receive the crank, and a weight adjustably secured to the last named lever.

2. A direction indicator comprising a casing, a supporting element in said casing, a shaft journaled in said supporting element, 60 a crank formed on said shaft, an indicator secured to said shaft, an operating lever pivoted to the supporting element above the shaft and having its lower end bifurcated to receive the crank, electromagnets carried by 65 the supporting element and arranged on opposite sides of the operating lever and below its pivot, an armature plate secured to the operating lever and extending to a point adjacent its bifurcation, lateral wings formed 70 on said plate and disposed on each side of the operating lever adjacent the magnets.

In testimony whereof I affix my signature in presence of two witnesses.

WILLIAM F. DORRIDA.
